CLAIM

The ornamental design for thermometer probe, as shown and described.

DESCRIPTION

FIG. 1 is a perspective view of a thermometer probe showing a first image in a fourth embodiment of the claimed design;

FIG. 2 is another perspective view thereof;

FIG. 3 is a front view thereof;

FIG. 4 is a side view thereof;

FIG. 5 is a top view thereof; and,

FIG. 6 is a bottom view thereof.

The broken lines of FIGS. 1-6 are for illustrative purposes only and form no part of the claimed design.
